UNITED STATES PATENT OFFICE.

DAVID HANNEY, OF TURNER, ILLINOIS.

VARIABLE EXHAUST FOR LOCOMOTIVES.

SPECIFICATION forming part of Letters Patent No. 432,704, dated July 22, 1890.

Application filed March 20, 1890. Serial No. 344,604. (No model.)

To all whom it may concern:

Be it known that I, DAVID HANNEY, a citizen of the United States, residing at Turner, in the county of Du Page and State of Illinois, have invented certain new and useful Improvements in a Variable Exhaust for Locomotives, of which the following is a full, clear, and exact description, that will enable others to make and use the same, reference 5 being had to the accompanying drawings, forming a part of this specification.

This invention relates to an improved device whereby the area of the exhaust-passage of a steam-engine may be varied, as will be 15 hereinafter set forth.

The object is to provide a simple and convenient device of this character, which will be easy of manipulation and so constructed as not to be liable to become clogged and the 20 working parts stuck.

Figure 1 is a broken-away vertical longitudinal section of the front end of a locomotive-boiler, showing the relative position of my improved device; Fig. 2, a horizontal section 25 in plane 2, Fig. 1; and Fig. 3, a vertical section in plane 3, Fig. 3.

In the drawings, A represents the smoke-box, A' the stack, A² the exhaust-pipe, and A³ the exhaust opening or passage. The 30 lower part of the short tubular cap B is provided interiorly with the annular shoulder a, (see Fig. 3,) and slips down over the terminal end of the exhaust-pipe proper until said shoulder comes to a bearing, as shown, and is 35 removably secured in position with reference to the exhaust-pipe by means of a number of set-screws a'.

The cap B is provided in the upper part and on opposite sides with the segment openings or ports a² a³, (see Figs. 2 and 3,) in which are seated the movable valve members C C, the inner adjacent edges a⁸ a³ of which are curved out to correspond with the exhaust-passage and beveled, as at a⁴, to contract the 40 passage in an upward direction, as shown in Fig. 3.

The valve parts or members C C move in a horizontal plane, and are shown in their in-

nermost position, contracting the exhaust-passage to its narrowest limit. These valve 50 parts have an outward movement in opposite directions far enough to uncover the full area of the exhaust-pipe. These valve parts are provided on their respective outer edges with the bifurcated lugs b b, in which are inserted 55 the respective inner ends of the angular or bell-crank levers D D, and secured thereto by the pivot-pin b'. The outer ends of these levers and the flattened end of the socket-piece d are secured together by the pivot-pin d'. The arms, 60 E E are formed on the cap B, and support the bell-crank levers D D at their central points, the pivot-pins d² d² forming the fulcrum-bearing on which said levers rock in the operation of imparting the required lateral movement 65 to valve members C C. The rod or operating-handle F is inserted in the socket-piece d and leads into the engine-cab, from which the device may be conveniently controlled by the engineer. The apertures or holes in the joining 70 ends of the angle-levers D D and the socket-piece d, through which the connecting pivot-pin d' is inserted, are somewhat enlarged or widened, so as to provide for a free movement of these parts. By this arrangement the area of the exhaust-passage may be 75 varied as the working of the engines may require in relieving the cylinders and flues of any undue strain.

Having thus described my invention, what I 80 claim as new, and desire to secure by Letters Patent, is—

In a variable exhaust, the combination, with the exhaust-pipe, of the tubular cap having ports or openings therein, the valve members movably inserted in said openings, the angular levers pivoted at their inner ends to said valve members, the arms in which said levers are fulcrumed, and the socket-piece and operating-rod connecting the outer ends 85 of said levers, substantially as and for the purpose set forth.

DAVID HANNEY.
